OIL BURNER

Harold H. Fletcher, Story City, Iowa

Application March 9, 1938, Serial No. 194,872

5 Claims. (Cl. 158—91)

This invention relates to improvements in oil burners, and particularly of that type adapted to be placed in small heating or cooking stoves such as are used for domestic heating or cooking and of the type employing a fire bowl in which the oil is admitted to the bottom of the bowl and evaporated and gasified by temperatures produced by the combustion of the fuel. In this type of burner the fuel, when vaporized and gasified, is burned with a rich mixture so as to produce a long and yellow flame extending upwardly through the throat of the fire bowl into the combustion chamber of the heater.

One difficulty heretofore experienced with this type of burner has been that combustion was not complete, and a smoky flame resulted, which tended to smoke up the interior of the heating stove, and also a considerable loss in fuel resulted. It is, therefore, the object of my invention to provide an improved burner construction wherein the air and gases of combustion will be more uniformly mixed and better combustion obtained.

A further object is to provide means for delivering into the generated gases of an oil burner a certain percentage of heated air in such a manner as to avoid currents of cold air intermixing with the unburned gases, wherein the combustion will be more complete and a saving in fuel realized.

My invention consists in the construction, arrangement and combination of the various parts of the device, whereby the objects contemplated are attained, as hereinafter more fully set forth, pointed out in my claims, and illustrated in the accompanying drawing, in which:

Figure 1 is a vertical central sectional view of a heater showing my improved burner therein.

Figure 2 is a diagrammatical view of my improved burner illustrated in dotted lines, and auxiliary means for further increasing the mixing effects between the gases and the incoming air, said auxiliary means being shown in solid lines.

Figure 3 is an enlarged detail sectional view taken on the line 3—3 of Figure 1.

Figure 4 is an enlarged detail sectional view taken on the line 4—4 of Figure 3.

I have used the numeral 10 to indicate the walls of a heater enclosing the combustion chamber 11, the numeral 12 indicating the casing surrounding the heater. Supported in the bottom end of the chamber 11 is my improved burner comprising a bottom 13 and an upright side wall 14, the wall 14 being preferably of cylindrical

form and having near its top end an inwardly projecting annular flange 15, said flange being inclined slightly upward. The inner edge of the flange 15 is provided with a cylindrical shell 16 to form the burner throat.

Spaced above the flange 15 is a second flange 17 so as to provide what I shall term a pre-heating chamber 18 between the two flanges. The upper end of the wall 14 is provided with an annular plate 19 spaced above the plate 17 to form a second or super pre-heating chamber 20. The wall 14 is provided with a number of rows of openings 21 for permitting air to enter through the space 22 provided between the walls 14 and the wall 10, the said space being open at its bottom end and closed at its top end by the outer edge of the plate 19. Immediately beneath the flange 15 is a row of openings 23 which are considerably smaller than the openings 21 and placed close together.

Formed in the flange 15 near its outer edge is a circular row of openings 24, each of the openings 24 being preferably in radial alignment with a corresponding opening 23, as clearly indicated in Figure 3. The wall 14 is also provided with a row of openings 25 communicating with the chamber 18. A row of openings 26 is also provided communicating with the chamber 20. The opening 27 in the plate 19 is preferably slightly larger than the top of the shell 16 and spaced slightly above it so as to provide a passage 28 from the chamber 20 to the combustion chamber 11. The usual smoke stack 29 is provided in the upper end of the wall 10, and a fuel pipe 30 is provided for delivering liquid fuel to the upper surface of the bottom member 13.

The operation of my burner is substantially as follows:

Liquid fuel, such as distillate, is permitted to flow to the upper surface of the bottom member 13, where it is ignited and allowed to burn until a considerable amount of temperature has been established, at which time other fuel will be vaporized by the heat, resulting in a rich mixture of gas and air, at which time the original flame will be extinguished due to a lack of sufficient air to maintain the combustion. Air entering the openings 21 will tend to support combustion resulting in long smoky and irregular flames protruding inwardly from each of said openings and upwardly through the throat 16. These irregular flames result from an improper mixture of air and gases. It will readily be seen that a liquid fuel in the bottom of the body or container tends to rise in clouds of rich gases intermingling

through and between currents of cold air entering the openings 21, resulting in a considerable amount of gases passing upwardly through the combustion chamber into the stack 29 without being burned. On account of the uneven mixture of fuel gases and air a considerable amount of noise results due to miniature explosions of that portion of the gas and air properly mixed to support an instantaneous combustion, while other portions or clouds of the mixture are too rich, and still other portions too thin, to support combustion. The above conditions as set forth are those resulting from a burner construction having air openings improperly proportioned and arranged. I have found by experimenting that by adding the row of openings 23 of comparatively small diameter and arranged closely together so as to feed small jets or streams of air into the generating chamber below the baffle plate 15, and in addition therewith introducing jets of downwardly projecting air against the said incoming horizontal jets, the second jets of air being heated, that a more uniform mixture is produced and the fuel made more combustible. Air entering the openings 25 into the chamber 18 will become heated and ejected through the said openings 24 which are of such size that a comparatively high velocity of air takes place as it is ejected from said openings. This air entering the generating chamber striking the jets of air entering the openings 23 will cause the two jets of air to be broken up and diffused and result in the downward and inward currents of air intermingling and mixing with the upward and inward currents of air and flames from the openings 21, thereby producing a more uniform mixture resulting in clean hot flames passing upwardly through the throat 16 and into the interior of the combustion chamber 11. Air entering the openings 26 into the upper pre-heating chamber will become heated and discharged upwardly and inwardly and around said flames through the throat 16, to produce excess heated air for completing the combustion of the heavier and slower burning gases.

Thus, it will be seen that I have provided a burner so constructed and arranged that liquid fuel may be delivered to the bottom of the generating chamber and become converted into vapors and gases having means whereby air may be introduced so as to produce a long, yellow, clean flame in which the combustion is completed before the products of combustion enter the stack 29, resulting in a perceptible saving in the amount of fuel consumed, as well as in a burner which can be more easily controlled, wherein combustion will be complete regardless as to whether or not fuel is being fed in small quantities or in larger quantities. In the use of certain kinds of fuel, and under certain chimney conditions wherein the draft is not uniform, it is sometimes desirable to insert in the throat of the burner a downwardly extending perforated cylinder 31, as illustrated in Figure 2, said cylinder being provided with a large number of openings 32 so as to retard the rapid flow of fuel gases and air to the throat 16, in such a manner that the incoming pre-heated air from the openings 23 and 25 will better mix the gases and air before entering the burner throat. I find that this cylinder 31 also tends to reduce the noise of the flame.

On the under edge of the flange 15 I have provided a downwardly extending flange 33 which tends to direct the air from the openings 23 and

24, downwardly for better diffusion with the gases, and also tends to eliminate noise.

I claim as my invention:

1. An oil burner including a generating and mixing bowl having a cylindrical upright wall, the upper edge of said wall being provided with an annular cover plate, a second annular plate within said wall and beneath the cover plate, a third plate beneath the second plate, the inner edge of said third plate supporting an upwardly projecting wall to form a throat having its upper edge terminating near the inner edge of the cover plate to provide a narrow annular outlet passage from the heating chamber between the uppermost and second plates, a second heating chamber being formed between the second and third plates, the outer wall of each of said heating chambers having an annular row of horizontal openings to admit air to said chambers, the third plate being provided with an annular row of vertical openings near its outer edge, the upright wall having a row of horizontal openings beneath the third plate, each of the openings in the outer edge of the third plate being in radial alignment with a corresponding horizontal opening of the last said row of openings wherein secondary air from the second chamber and said aligned openings will be delivered downwardly and inwardly into the generating chamber at high velocities and in a diffused manner, and wherein air from the upper heating chamber will be delivered upwardly from the upper edge of said throat into a combustion chamber above said throat.
2. An oil burner, comprising a casing, a fire bowl within the lower end of the casing, of smaller diameter to provide a space between them, the upper end of said fire bowl having a cover plate covering the upper end of said space and projecting inwardly at the upper end of said bowl to divide the casing into generating and combustion chambers, a second annular plate within said wall and beneath the cover plate, a third plate beneath the second plate, the inner edge of said third plate supporting an upwardly projecting wall to form a throat, having its upper edge terminating near the inner end of the cover plate to provide an annular outlet from the heating chamber formed between the upper and second plates, a second heating chamber being formed between the second and third plates, the outer wall of said fire bowl having annular rows of horizontal openings to admit air to said chambers, the third plate being provided near its outer edge with a row of vertical openings, the wall of said fire bowl having a row of horizontal openings beneath the third plate, each of the openings in the outer edge of the third plate being in radial alignment with a corresponding one of the last said openings, wherein secondary air from the second chamber and said aligned openings will be delivered downwardly and inwardly in said generating chamber at high velocities and in a diffused manner, and wherein air from the upper heating chamber will be delivered upwardly from the upper edge of said throat into said combustion chamber.
3. An oil burner, comprising a casing, a fire bowl within the lower end of the casing of smaller diameter, the upper end of said fire bowl having an inwardly projecting flange to form a throat and to divide the casing into generating and combustion chambers, said inwardly projecting

flange being formed hollow to provide upper and lower heating chambers, the walls of said fire bowl having openings to admit air from the space between the fire bowl and the casing wall into the generating chamber, the outer wall of the flange having openings to admit air to the heating chambers, the bottom of the lower heating chamber being provided near its outer edge with a row of openings, the wall of the fire bowl having a row of openings beneath the bottom of the lower chamber, each of the openings of the outer edge of said chamber being in radial alignment with a corresponding one of the last said row of openings wherein secondary air from the lower heating chamber will be delivered downwardly and inwardly into the generating chamber at high velocities and in a diffused manner, the upper and inner corner of the upper heating chamber having a passage wherein heated air from the upper chamber will be delivered upwardly at a point at the upper end of said throat into the combustion chamber.

4. An oil burner including a generating and mixing bowl having a cylindrical upright wall, the upper edge of said wall being provided with an annular cover plate, a second annular plate within said wall and beneath the cover plate, a third plate beneath the second plate, the inner edge of said third plate supporting an upwardly projecting wall to form a throat having its upper edge terminating near the inner edge of the cover plate to provide a narrow annular outlet passage from the heating chamber between the uppermost and second plates, a second heating chamber being formed between the second and third plates, the outer wall of each of said heating chambers having an annular row of horizontal openings to admit air to said chambers, the third plate being provided with an annular row of

vertical openings near its outer edge, the upright wall having a row of horizontal openings beneath the third plate wherein secondary air from the second chamber and said aligned openings will be delivered downwardly and inwardly into the generating chamber at high velocities and in a diffused manner, and wherein air from the upper heating chamber will be delivered upwardly from the upper edge of said throat into a combustion chamber above said throat.

5. An oil burner, comprising a casing, a fire bowl within the lower end of the casing of smaller diameter to provide a space between said walls, the upper end of said fire bowl having a cover plate covering the upper end of said space and projecting inwardly at the upper end of said bowl to divide the casing into generating and combustion chambers, a second annular plate within said wall and beneath the cover plate, the inner edge of said second plate supporting an upwardly projecting wall to form a throat having its upper edge terminating near the inner end of the cover plate to provide an annular outlet from the heating chamber formed between the upper and second plates, the outer wall of said fire bowl having annular rows of horizontal openings to admit air to said chamber, the said second plate being provided near its outer edge with a row of vertical openings, the wall of said fire bowl having a row of horizontal openings beneath the second plate, each of said openings being in radial alignment with a corresponding one of the last of said openings wherein secondary air from said heating chamber and said aligned openings will be delivered downwardly and inwardly in said generating chamber at high velocities and in a diffused manner.

HAROLD H. FLETCHER.
